US00D566051S

(12) **United States Design Patent** (10) **Patent No.:** **US D566,051 S**
(45) **Date of Patent:** **** Apr. 8, 2008**

(54) **CONTROL MODULE**

(75) Inventor: **Gururaj Govindasamy**, Glenview, IL (US)

(73) Assignee: **Shure Acquisition Holdings, Inc.**, Niles, IL (US)

(**) Term: **14 Years**

(21) Appl. No.: **29/275,520**

(22) Filed: **Dec. 28, 2006**

(51) **LOC (8) Cl.** **13-03**

(52) **U.S. Cl.** **D13/168; D14/218**

(58) **Field of Classification Search** **D13/158, D13/162, 168, 171; D14/218, 223, 240; D10/104, 106; D3/207, 208, 218; 455/151.1-151.4, 455/152.1, 352-355**

See application file for complete search history.

(57) **CLAIM**

The ornamental design for a control module, as shown and described.

DESCRIPTION

FIG. 1 is a front right isometric view of a control module that shows my claimed design;

FIG. 2 is a rear right isometric view thereof;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

The broken lines in FIGS. 1 through 8 are for illustrative purposes only and form no part of the claimed design.

1 Claim, 4 Drawing Sheets
